Elmer J. Key, of Lowell, Mass.

Assignor to

The Lowell Manufacturing Company, of the same place

Letters Patent No. 1973-Dated July 19th 1864.

Design for a Carpet Pattern

The schedule referred to in these Letters Patent and making part of the same

Is as follows:

Be it known that Elmer J. Key, of Lowell, in the County of Middlesex and State of Massachusetts, have originated and designed a new pattern for carpets or other fabrics, of which the following is a full, clear and exact description, reference being had to the accompanying drawings, making part of this specification.

In the four corners are sections of shells, flowers, and vicinal figures similar to A. and B. respectively.

The remaining figures of the design are combinations of lines, sprigs and berries arranged as shown in the drawings.

The colors employed for the different portions of the design, may be varied to suit the taste and wish of the manufacturer.

Claim

What I claim as my invention and desire to secure by Letters Patent, is the design or pattern for carpets or other fabrics herein set forth.
